(57) **CLAIM**

I claim the ornamental design for a finger sheath with retractable stylus, as shown and described.

DESCRIPTION

FIG. 1 is a rear, left, top view of a finger sheath with retractable stylus showing my new design;

FIG. 2 is left side elevational view thereof;

FIG. 3 is a right side elevational view thereof;

FIG. 4 is a top plan view thereof;

FIG. 5 is a bottom plan view thereof;

FIG. 6 is a front elevational view thereof;

FIG. 7 is a rear elevational view thereof;

FIG. 8 is a rear, left, top view of the finger sheath with retractable stylus shown in an alternative position of use, wherein the stylus is depicted in a retracted or closed configuration;

FIG. 9 is a left side elevational view thereof;

FIG. 10 is a right side elevational view thereof;

FIG. 11 is a front elevational view thereof; and,

FIG. 12 is a rear elevational view thereof.
